UNITED STATES PATENT OFFICE.

HARRY J. RYAN, OF TROY, NEW YORK.

DESIGN FOR A WATER-HEATER.

45,696.

Specification for Design.

Patented Apr. 28, 1914.

Application filed January 14, 1914. Serial No. 812,146. Term of patent 14 years.

To all whom it may concern:

Be it known that I, HARRY J. RYAN, a citizen of the United States, residing at Troy, in the county of Rensselaer and State of New York, have invented a new, original, and ornamental Design for Water-Heaters, of which the following is a specification, reference being had to accompanying drawings, forming part thereof.

The single figure of the drawing is a view in perspective of a water heater, showing my new design.

I claim:

The ornamental design for a water heater as shown.

HARRY J. RYAN.

Witnesses:

ROSE A. LEDUC,

FRANK C. CURTIS.
